MAXIMILIAN P. LEVINE, OF CHICAGO, ILLINOIS.

COMBINED FOLDER AND RETURN-ENVELOP.

1,089,486.

Specification of Letters Patent. Patented Mar. 10, 1914.

Application filed April 7, 1911. Serial No. 619,614.

To all whom it may concern:

Be it known that I, MAXIMILIAN P. LEVINE, a citizen of the United States, residing at Chicago, in the county of Cook and State of Illinois, have invented certain new and useful Improvements in a Combined Folder and Return-Envelop, of which the following is a description.

My invention belongs to that general class 10 of devices known as folders, envelops and the like, and relates particularly to a combined folder, letter or circular and envelop.

My invention has among its objects the 15 production of a simple, convenient, economical, durable, efficient and satisfactory device of the kind described for use wherever found applicable. The device is simple in construction, economical in manufacture and use, and efficient in bringing the desired results. It is attractive and demands attention, and may be used when desired with the privacy of a letter. The uses are varied and practically unlimited.

To this end my invention consists in the 20 novel construction, arrangement and combination of parts herein shown and described, and more particularly pointed out in the claim.

In the drawings, wherein like reference 25 characters indicate like or corresponding parts, Figure 1 is a plan view of one side of one form of my device opened or unfolded. Fig. 2 is a similar view of the reverse side of the same. Fig. 3 is a sectional view 30 of the same, taken substantially on line 3, 3 of Fig. 1. Fig. 4 is a sectional view of the same device, folded for delivery. Fig. 5 is a cross sectional view of the detached envelop with an order blank therein. Fig. 6 35 is a plan view of one side of another modified form, unfolded. Fig. 7 is a plan view of the reverse side of the same folded. Fig. 8 is a plan view of a portion of a modified construction, and Fig. 9 is a plan view of 40 a portion of another slightly modified construction.

Broadly speaking, my invention comprises an envelop and a folder or circular, upon which suitable information may be 45 placed, and which may include an order blank or inquiry slip, the parts being preferably detachably connected together and arranged to be folded together so as to protect the envelop, whereby when the parts 50 are so folded, the device will be in condition to be delivered through the mails, or in any

equivalent way, with the address on the folder. Samples or other matter may be inclosed in the envelop and sent with the circular. The recipient of the folder and envelop may, if desired, detach the envelop, which is preferably sent out addressed, and employ the same in the ordinary manner in transmission to the sender of the folder, or other desired person whose address may be 60 upon the envelop.

Referring to Figs. 1 to 5 inclusive, A represents the circular, letter, order blank or folder, or the equivalent, and B the envelop, the two being preferably detachably secured 65 together, as before mentioned. In the form shown in these figures, the parts A and B are formed from one piece of stock or material, the same being suitably scored for folding, and scored, perforated or arranged 70 in an equivalent manner to facilitate detaching the parts. Referring particularly to Figs. 1, 2 and 3, 1 represents a portion of the envelop, as shown the flap, and 2 and 3 the two sides of the envelop, 8, 8 being flaps 75 or extensions on one of the sides forming the ends of the envelop. The envelop shown in these figures is what is commonly known as a side seam envelop, a center seam envelop being hereafter described. For convenience I have used suitable reference 80 characters for designating the parts, and the same reference characters with an exponent for denoting or showing the opposite or reverse side of the same part. The 85 circular or folder part shown in these figures may consist of any desired number of parts arranged in any form. The circular shown also comprises an order blank, or inquiry slip 4, which is preferably suitably scored 90 at 11, so that it may be detached, and to the blank 4 is added a circular or additional part 5, 14 being the scoring line or point at which the two are detachable. The circular 95 part 5 is scored at 15, and if desired, an extending or additional flap 6 may be added, on which may be provided mucilage 22, or 100 its equivalent, so that the package may be sealed when folded, as hereafter described. The scoring or folding lines are represented 105 by the numerals 15 and 16, the line 11 also being a folding line as well as a detaching point.

In Fig. 4 is shown the preferred way of folding the device, and referring to this figure, it will be noted that the envelop is 110 inclosed by the parts 4, 5 and 6, the flap 1 on

the envelop being turned back against the front side 2, and upon the outside of the circular, as shown in the unfolded circular in Fig. 2, is placed the address 25¹ of the one 5 who is to receive the circular or package. If the folder and envelop are to be sent through the mails, the flap 6 may be secured down either by the usual and well known form of wire clip, by pasting the same, or in any 10 other desired way, the method depending upon the privacy desired. In that case it would go as unsealed matter, while in the other it would be sealed. If the circular is 15 in the nature of a personal letter, as is frequently the case, and it is desired to put the name and address of the receiver in the body of the circular, the same may be done in any suitable way. Ordinarily the circular or letter part is printed, as for example, 20 in the well known imitation type-writer style; then the name and address of the person receiving the same filled in at a suitable place, on a typewriter. In this figure I have shown the recipient's name at the end 25 of the letter or circular. However, it may be placed at any other point on the circular or blank, as for example, as illustrated and hereafter described. By manipulating the circular the recipient's name may be simultaneously placed on the front of the circular, as well as upon the outside of the folded circular, by folding the same along the line 15, so that the sides 5¹ and 4¹ are together. A piece of carbon or transfer paper, 30 or the equivalent, is then positioned or arranged between the two. If the name, as for example "John Doe, etc." is written as at 25, the same will be transferred to the side 5¹, as indicated at 25¹ in Fig. 2, so that 35 it is not necessary to direct the folder on the outside by a separate operation. The resulting saving in time, labor and expense is obvious, and can be readily appreciated.

Where the order blank 4 is made a part of 40 the circular, the same may be arranged at any desired place, either at the ends or intermediate the circular, and it is obvious that the same need not be formed integrally, or secured to the circular or envelop, but may 45 be carried within the envelop. As shown in these figures, however, it is arranged adjacent the envelop and integrally connected thereto and to the circular. It is not necessary that the name and address of the receiver of the matter be put on the order blank, as shown, as it may be arranged at 50 any other place. The purpose of placing it on the order, or rather the blank, is so that when the blank is returned in the return envelop, the name of the sender of the order, 55 that is the one returning the same, will be legible. As a matter of fact the order blank, if desired, may be so arranged that the person returning the same need not write or fill

in anything before returning the same to the 65 original sender.

In order that the working or use of the device may be understood, let us assume that a circular or folder and envelop similar to that shown in Fig. 1, is sent out by a publisher, merchant or other person, and is in the form of a letter. The letter or circular for instance, may be printed in any desired style, as for example, in imitation type-writer, as mentioned, and the name of the 70 recipient and address be then put on as described, or as desired. If the circular is folded and a piece of carbon paper used as described, the outside of the folder is also addressed at the same time that the name 75 and address are placed on the face of the circular. The address of the person to whom it is desired that the reply shall be sent is printed or otherwise placed upon the envelop before sending, and it may also be 80 stamped before sending, if desired. If the order or inquiry blank is not formed as part of the circular, as described, or it is desired to send a sample, the same may be placed in 85 the return envelop. The circular and envelop are then folded, for example as shown in Fig. 4, with the name and address of the person to receive the same on the outside. The parts may be held together either with 90 a clip or the equivalent, or by pasting the flap down. The same is then forwarded in any desired way, for example by mail. Upon receipt of the device the recipient, if 95 he desires, may then detach the return envelop and order, if an order is included, 100 place his order in the envelop together with the remittance required, as for example as set forth on the order blank or the letter, and the flap 1 of the envelop turned over to the opposite side and tucked in the envelop, 105 or pasted against the side 3¹ of the envelop. The envelop may then be stamped, if not already stamped, and mailed. If the stamp 110 is omitted, the envelop being sealed, the postage will be collected by the original sender. It will thus be seen that if the order is so arranged, the remittance and order may be inclosed and the same returned to the original sender without requiring any 115 writing by him at all. The envelop may of course be detachably secured to the circular in any other way, several forms of the device being hereafter shown and described. The envelop and circular may also be of any 120 form or size and include any information applicable or desired.

It will be noted by referring to Fig. 1, that I preferably indicate the detaching points by suitable directions. By attaching the addressed envelop to the circular, I provide an addressed return carrier for returning the remittance as well as for the order or letter. This is particularly important

for it not only brings the order, but brings the money with it, avoiding the expense of a collection later, as well as carrying a great number of book accounts. The uses of the device are unlimited, and it is impossible to give examples of the many modifications that may be formed. I have therefore only shown several forms of my device.

In the modified form shown in Figs. 6 10 and 7 the circular is substantially similar, but the envelop is what is known as a center seam envelop, which comprises the front 41, flap 40 and side flaps 47. In this case the sealing flap 42 extends into the circular 15 or folder part 43, the same being detachable on the line 45. As shown, the flap may be provided with mucilage as at 49. The detach line 45 may be as shown, or it may extend in a straight line across the paper. In 20 this figure the order blank 44 is shown at the top, the same being detachable at the detach line 48. As with the other forms the order blank may be arranged where desired. At the top or end of the circular 25 may be arranged a flap 50, provided with paste or mucilage 51 for sealing the folder in sending, if desired. A slightly different way of addressing the outside of the folder is illustrated in this form. An opening or 30 hole 53 is cut in the circular, so that the name and address 52 on the inside of the circular will show through when the circular is folded. (See Fig. 7). The same would be true if the address 52 were placed 35 below the detach line 46, for example as shown in Fig. 1, the only difference being in the way that the device is folded.

In Fig. 8 is illustrated another form of device, in which the envelop is separate from 40 the circular 60, but detachably secured thereto. Referring to this figure, the envelop comprises the parts 61, 62, 63 and 66, the same being formed with extended flaps 64, by which the envelop is secured to the circular 45 60. The flap 64 may be perforated or scored at 65 to facilitate detaching. A modified construction is also shown in Fig. 9, in which 70 represents the circular to which is detachably secured the envelop 71 provided with a flap 72. In this form the flap 72 is formed with a detachable part 73, 74 being the detach line. In connection with these two forms it may be noted that an envelop may be constructed substantially as 55 shown in Fig. 1, in which the order blank, instead of being an order, would be a flap

provided with paste, which would be the equivalent of the flap 64 shown in Fig. 8. With this form the envelop could be detachably secured to any circular or letter. 60 It may also be noted that although an envelop is shown only at one end of the circular, the opposite end of the circular may be similarly provided with an envelop so that there is an envelop at each end. This 65 construction is so obvious that it is considered unnecessary to further illustrate the same.

Having thus described my device, it is obvious that various immaterial modifications may be made in the same without departing from the spirit of my invention, hence I do not wish to be understood as limiting myself to the particular form, construction, arrangement, or combination of 75 parts herein shown and described, nor do I wish to limit myself to any particular use of the circular, or information, etc., contained upon the same.

What I claim as new and desire to secure 80 by Letters Patent is:—

In a device of the kind described, the combination of an envelop comprising a front or address side and a rear side connected thereto, said sides being separated 85 from one another at their upper edge, a flap projecting from the upper edge of the front side of the envelop and normally folded downwardly over said front side, a folder projecting from the upper free edge of the 90 rear side and connected thereto by a weakened line, the said folder being of a width throughout substantially co-extensive with the width of the envelop and of a length to fold entirely around the envelop and having 95 a sealing flap to engage the body part of the folder holding the latter in place and entirely inclosing the envelop without engaging any portion of the envelop, the folder being adapted to be removed at the 100 weakened portion and the flap of the envelop being thereupon adapted to be folded from its position against the front side of the envelop to a position over the rear side and to be sealed to the latter. 105

In testimony whereof, I have hereunto signed my name in the presence of two subscribing witnesses.

MAXIMILIAN P. LEVINE.
